Paul Witzel

UNITED STATES PATENT OFFICE.

PAUL WITZEL, OF BERLIN-WEISSENSEE, GERMANY.

AUTOPLANE.

1,073,648.

Specification of Letters Patent. Patented Sept. 23, 1913.

Application filed May 1, 1913. Serial No. 764,934.

To all whom it may concern:

Be it known that I, PAUL WITZEL, a subject of the German Emperor, and resident of Berlin-Weissensee, Germany, have invented certain new and useful Improvements in Autoplanes, of which the following is a specification.

This invention relates to an improved autoplane, which is so constructed that it can be used on the ground, as well as in the air or on the water.

The improved autoplane is represented on the accompanying drawing, in which—

Figure 1 is a side view, and Fig. 2 a plan view, of the same, while Figs. 3, 4 and 5 are diagrammatical sections on the lines A—B, C—D and E—F of Fig. 1 respectively.

The autoplane is mounted on a portable truck *a*, by means of which it can be run on the ground. To raise the apparatus, four lateral height-wings, two on each side, are provided, by which the autoplane can be lifted directly from the place, where it stands, without necessitating for this purpose a starting plane like other apparatus. The height-wings *b* are coupled with the main-shaft of the apparatus by chain-gearings and adapted to turn on the right hand side to the right and on the left hand side to the left (see arrows, Fig. 4), whereby they suck-off the air beneath the draft planes and thus lift the autoplane. Upon the latter having reached the desired height, the front propeller *c* and the two rear propellers *e*, *f* are switched-on, and the autoplane is moved forward.

At the head of the autoplane, a wind-catcher *g* and a height steering device *h* are arranged, while at the tail two stabilization-planes *i* and the side steering device

d are provided. A compressed-air motor *k* is mounted behind the front propeller. With the motor shaft *l*, the height-wings *b*, as mentioned, and the rear propellers *e*, *f* are coupled. Beside the passengers' room *n*, an oil-container *o* is provided for an automatic lubrication of all bearings. The stabilization-planes *i* are operated from *p* with the aid of levers, so as to keep the autoplane in balance.

A gas-reservoir *r* is mounted in the autoplane, for assisting in carrying the same.

a are adjustable water-runners, which, when lowered, permit of the apparatus being used as a hydroplane.

I claim:

In an autoplane, in combination, a portable truck to carry the same on the ground, a wind-catcher and a height steering device at the front of the autoplane, a front propeller behind the latter, adjustable stabilization-planes, two rear propellers and a side steering device all arranged at the tail of the autoplane, a motor behind the front propeller having a main-shaft coupled with said propellers, four laterally arranged height-wings coupled with said shaft, a gas-reservoir to assist in carrying the autoplane in the air, and adjustable runners adapted, when lowered, to use the apparatus as a hydroplane, substantially as described and shown and for the purpose set forth.

In testimony whereof I have hereunto set my hand in the presence of two subscribing witnesses.

PAUL WITZEL.
